CLAIM

We claim the ornamental design for a portion of a display screen, as shown and described.

DESCRIPTION

FIG. 1 is a front view of an image for a portion of a display screen showing our new design.

FIG. 2 is a front view thereof with region labeled "A" and annexed with broken line to indicate where the enlargement of FIG. 3 is taken from; and,

FIG. 3 is an enlarged view for clarity of region A indicated in FIG. 2.

The broken line showing of a square, a display screen and the remainder of the taskbar in FIGS. 1, 2 are for illustrative purposes only and form no part of the claimed design. Additionally, the broken line circular region within the taskbar button forms no part of the claimed design.
